(57) **CLAIM**

I claim the ornamental design for a wireless charger, as shown and described.

DESCRIPTION

FIG. 1 is a perspective view of a wireless charger showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view thereof, showing the foldable part in a closed position; and,

FIG. 9 is another perspective view thereof, showing the retractable part in an open position.

The broken lines depict portions of the wireless charger and form no part of the claimed design.

1 Claim, 9 Drawing Sheets
